UNITED STATES PATENT OFFICE.

JOHN CHARLES KORTH, OF NEW YORK, N. Y.

GRIP DUMB-BELL.

1,026,215.

Specification of Letters Patent.

Patented May 14, 1912.

Application filed June 29, 1911. Serial No. 635,924.

To all whom it may concern:

Be it known that I, JOHN CHARLES KORTH, a citizen of the United States, and a resident of the city of New York, borough 5 of the Bronx, in the county and State of New York, have invented a new and Improved Grip Dumb-Bell, of which the following is a full, clear, and exact description.

The invention relates to physical exercisers, and its object is to provide a new and improved grip dumb-bell, arranged to combine a dumb-bell with a hand grip exerciser, with a view to provide the desired weight and to cause an alternate tension and relaxation of the muscles of the hand, wrist and arm when used for a physical exerciser, and to permit of increasing the weight when it is desired to exercise with the device in the form of a dumb-bell without the grip exerciser. 15

For the purpose mentioned, use is made of a dumb-bell, a grip and a spring connecting the said bell and grip with each other.

A practical embodiment of the invention 25 is represented in the accompanying drawings forming a part of this specification, in which similar characters of reference indicate corresponding parts in all the views.

Figure 1 is a side elevation of the grip 30 dumb-bell, parts being in section; Fig. 2 is an elevation of one end of the same; Fig. 3 is a side elevation of the exerciser arranged as a double-weight dumb-bell, parts being in section; and Fig. 4 is a cross section of the 35 same on the line 4-4 of Fig. 3.

The exerciser illustrated in Figs. 1 and 2 consists essentially of the dumb-bell A, a hand grip B and a spring C connecting the dumb-bell A with the hand grip B at one 40 end thereof. The dumb-bell A consists of a handle A' and the bells A², A³, of which preferably one, the bell A², is provided with a radial cut-out portion A⁴, and the handle A' is provided with a longitudinal bore or 45 recess A⁵ opening into the cut-out portion

A⁴. The spring C is provided with a coil C' and terminals C², C³, of which the terminal C² removably engages the bore or recess A⁵, while the terminal C³ engages a 50 recess or bore B' formed in the hand grip B. The terminal C³ is preferably provided with a bend or kink (see Fig. 1) so that when the terminal is driven into the bore B', the bend or kink firmly engages the wall 55 of the bore B' to hold the grip against accidental displacement. A portion of the coil

C' extends within the recess A⁴ thus holding the spring C against transverse movement and thereby maintaining the dumb-bell A and the grip B in the desired relative 60 position, for convenient engagement with the hand when exercising, the user then taking hold, with the palm, of the handle A', and the grip B with the fingers. When this is done, the operator can swing the grip B 65 toward the dumb-bell A, thereby placing the spring C under tension, and when releasing the pressure the spring returns the grip B in an outward direction away from the dumb-bell A. 70

In order to limit the swinging motion in an outward direction of the grip B relative to the dumb-bell A, use is made of a stop D, preferably in the form of a rod provided at its ends with eyes D', D², of which the 75 eye D' engages the terminal C² in the cut-out portion A⁴, while the eye D² engages the terminal C³ adjacent the recessed end of the grip B. It is understood that by the use of the device sufficient weight is provided by having the dumb-bell A, and at 80 the same time an alternate tension and relaxation of the muscles of the hand, wrist and arm is had by the user alternately pressing the grip B and releasing the same. 85

It is understood that two of the exercisers described are usually made use of by a person exercising simultaneously with both hands, and when it is desired to use the exercisers as dumb-bells only, the terminal C² 90 of the spring C is drawn out of the bore A⁵ so as to permit using the dumb-bell A by itself. If more weight is desired the two dumb-bells A, which belong to a pair of exercisers, are connected with each other, as 95 indicated in Figs. 3 and 4, by engaging the cut-out portion A⁴ of one dumb-bell with the handle A' of the other dumb-bell so that the two dumb-bells are interlocked and can be readily taken hold of in one hand by 100 the user for dumb-bell exercises.

Having thus described my invention, I claim as new and desire to secure by Letters Patent:

1. An exerciser, comprising a dumb-bell, 105 a grip spaced from the dumb-bell, and a spring connected at its ends with the said dumb-bell and grip at one end thereof, the portion of the spring intermediate the ends of the dumb-bell and grip forming a fulcrum to allow the dumb-bell and grip to swing toward and from each other. 110

2. An exerciser, comprising a dumb-bell having a longitudinal bore, a grip having a longitudinal bore, and a coil spring having terminals engaging the said bores to connect the dumb-bell and grip with each other. 5
3. An exerciser, comprising a dumb-bell, a grip, a spring connecting the said dumb bell and grip with each other at one end, and a stop on the spring for limiting the 10 opening movement of the dumb-bell and grip.
4. An exerciser, comprising a dumb-bell having a longitudinal bore, a grip having a longitudinal bore, a coil spring having 15 terminals engaging the said bores to connect the dumb-bell and grip with each other, and a stop having hooks at its ends engaging the said spring terminals to limit the opening movement of the said dumb-bell and 20 grip.
5. An exerciser, comprising a dumb-bell having a longitudinal bore, a grip having a longitudinal bore, and a coil spring having terminals engaging the said bores to connect 25 the dumb-bell and grip with each other, the spring terminals for the grip having a kink to hold the grip against accidental displacement.
6. An exerciser, comprising a dumb-bell 30 provided with a cut-out portion in the bell and having a bore in the handle, a grip having a bore, and a coil spring extending in the said cut-out portion and having its terminals engaging the said bores.
- 35 7. An exerciser, comprising a dumb-bell, provided with a cut-out portion in the bell and having a bore in the handle, a grip having a bore, a coil spring extending in the said cut-out portion and having its terminals engaging the said bores, and a stop 40 having eyes at its ends, one of the eyes engaging the dumb-bell terminal of the spring at the said cut-out portion and the other end engaging the grip terminal of the spring adjacent the end of the grip. 45
8. An exerciser, comprising dumb-bells having cut-out portions in the bells, the cut-out portion of the bell of one of the dumb-bells being adapted to engage the handle of the other dumb-bell. 50
9. An exerciser, comprising a pair of dumb-bells having radially cut-out portions in the bells, the cut-out portion of the bell of one of the dumb-bells engaging the handle of the other dumb-bell to form a single 55 exerciser of the pair of dumb-bells.
10. An exerciser, comprising a dumb-bell, a grip, and a spring connecting the said dumb-bell and grip with each other at one end, the spring forming a fulcrum for the 60 dumb-bell and grip to swing toward and from each other.

In testimony whereof I have signed my name to this specification in the presence of two subscribing witnesses.

JOHN CHARLES KORTH.
